UNITED STATES PATENT OFFICE.

HOWARD W. GILBERT, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPLING.

1,199,034.

Specification of Letters Patent. Patented Sept. 19, 1916.

Application filed March 18, 1912. Serial No. 684,457.

To all whom it may concern:

Be it known that I, HOWARD W. GILBERT, a citizen of the United States, residing at Cleveland, Cuyahoga county, State of Ohio, have invented an Improvement in Car-Couplings, of which the following is a specification, reference being had to the accompanying drawings, forming part of the specification, in which—

10 Figure 1 is a plan view partly in section of my improved car coupler; Fig. 2 is a section on lines II—II of Fig. 1, and Figs. 3, 4, 5, 6, 7 and 8 show modified forms of my device.

15 My invention relates to car couplers, and is especially designed to provide an interlocking engagement between the coupler head and the tail of the knuckle which will positively prevent any vertical movement 20 of the knuckle-tail relative to the head.

In the accompanying drawings, in which I have shown my improvements as applied to a coupler of the type shown in a patent granted to Harry T. Krakau No. 1,040,551 25 dated October 8, 1912, 2 is the coupler head and 3 is the knuckle pivoted thereto by the pivot pin 4. 5 is the vertically movable lock which operates through an opening in the coupler head. The knuckle 3 has a rearwardly extending tail 6, the back or rear face of which has inclined and preferably wedged shaped surfaces 7. These wedged shaped surfaces 7, which extend both longitudinally and laterally of the coupler 30 head, are adapted to fit against corresponding inclined bearing surfaces 8 in the recess 9 of the coupler head and to be held by the lock 5 positively against the same. The lock 5 which moves vertically, has downwardly converging sides 5' so that it drops by gravity and wedges in the space between the coupler head 2 and the forward side 10 of the knuckle tail, thus holding the knuckle tail 6 with its wedge shaped rear 40 surfaces 7 firmly against the inclined bearing surfaces 8 as above described. This engagement of the knuckle tail between the inclined bearing surfaces 8 and the lock 5 not only prevents loose lateral motion of the knuckle, but also holds the knuckle tail against any vertical motion, so that there is provided an efficient interlock of the knuckle tail with the coupler head, preventing any motion whatever of the knuckle tail.

It has been found that under certain conditions of service, if there is any vertical looseness whatever of the knuckle in its bearings within the head, that an up and down movement of the knuckle tail may occur, which movement, especially when there is a strain upon the parts, may cause the lock to start creeping upwardly, and if the action is continued long enough, may cause it to creep far enough to release the knuckle tail and allow an uncoupling. Unless the knuckle tail has some positive engagement which prevents its vertical movement, however slight such movement may be, this creeping movement of the lock is liable to begin.

As the bearing surfaces of my device allow no play of the knuckle tail, the lock cannot tend to creep upward with the resultant danger of uncoupling. Moreover, it will be seen that any wear between the wedge shaped bearing surfaces 7 of the rear of the knuckle tail and the coating bearing surfaces 8 of the coupler head will be automatically taken up by the lock, since, because of its wedge shape, it will merely drop lower in the coupler head and will always bear securely and firmly on both the front face 10 of the knuckle tail, and on the coupler head opposite the recess 9 for the knuckle tail.

In Figs. 3 to 7 I show a number of modified forms of my device.

In Fig. 3 the rear face of the knuckle-tail 6^a has in it a groove extending over a portion of its surface, said groove having bearing surfaces 7^a sloping toward the center of the knuckle-tail which are adapted to contact with bearing surfaces 8^a on a corresponding ridge in the knuckle cavity 9^a.

In Fig. 4 I show a form which is just the inverse of my preferred form; that is, the knuckle cavity 9^b is made with its rear wall composed of two sloping surfaces 8^b, which extend inwardly to a point, and the knuckle-tail 6^b has a corresponding depression with bearing surfaces 7^b.

The form shown in Fig. 5 is similar to my preferred form, except that the bearing surfaces 7^c and 8^c are shortened, and instead of meeting to form a point there is a flat portion between them.

In Fig. 6 the knuckle tail 6^d is made with one diagonal face 7^d and the knuckle cavity

9^a has one corresponding face 8^a instead of the two pairs of bearing surfaces shown in my preferred form.

Fig. 7 shows a form similar to Fig. 5, except that there is an additional ridge on the knuckle tail 6^e and a corresponding groove in the knuckle cavity 9^e. In this form the bearing surfaces 7^e and 8^e co-act to accomplish the desired result.

10 In Fig. 8 there is a further modification, in which the rear of the knuckle tail 6^f has a convex surface 7^f and the wall of the knuckle cavity 9^f has a corresponding convex surface 8^f.

15 It is obvious that my improvement can be utilized in any Master Car Builder's type of coupler in which the knuckle is intended to be held rigidly.

What I claim is:

20 1. In a car coupler, a knuckle having a tail extending rearwardly into the coupler cavity, said knuckle tail having on its rear

face laterally inclined bearing surfaces, co-acting bearing surfaces on the wall of the coupler cavity, said surfaces being adapted 25 to prevent vertical movement of the knuckle, and a lock adapted to wedge the bearing surfaces on the knuckle tail firmly against the surfaces on the wall of the coupler cavity. 30

2. In a car coupler, a knuckle having a tail extending rearwardly into the coupler cavity, a set of converging surfaces upon the knuckle tail, a corresponding set of surfaces within the coupler cavity, said sets of 35 surfaces being adapted to be brought into wedging relation by the transverse movement of the knuckle tail, and a lock adapted to maintain said engagement whereby said knuckle is held from vertical movement. 40

HOWARD W. GILBERT.
